ELECTROSTATIC CONTROL OF FIBERS

Edgar S. Kennedy, Wayne, and Frederick C. Wedler, Media, Pa., assignors to American Viscose Corporation, Wilmington, Del., a corporation of Delaware

Application October 4, 1944, Serial No. 557,190

3 Claims. (Cl. 19—150)

1

This invention relates to the formation of seemingly continuous structures comprising substantially parallelized overlapping fibers directly from loose masses of disordered heterogeneously disposed fibers of spinnable length by a single step procedure.

Fibers adapted for spinning are obtained initially in the form of tangled masses in which the fibers are matted and clumped together. Even after subjecting the tangled fibers to an opening operation, they are in the form of loose masses in which the fibers project in all directions. In order to convert such loose masses into a structure in which the fibers are substantially all parallelized it is common practice to subject them to a series of more or less complicated mechanical operations including picking, carding, treatment in a roving doubler, and in a combing machine. Such operations have the disadvantage that they are wasteful, because a considerable quantity of the fibers are broken and must be discarded. Further, the severity of the many operations is such that the surfaces of the fibers are scarred and mangled, thus impairing the appearance and quality of articles formed therefrom in subsequent processing, and, if the fibers are lustrous, some of the lustre is dimmed, which is undesirable in some cases.

In accordance with the instant invention, the numerous pre-treatments conventionally employed precedent to formation of structures such as webs, bats, mats, spinnable slivers etc. are eliminated, and loose masses of disordered fibers of spinnable length are directly converted to an extremely compact, even, and heavy product in which the individual fibers are laid back upon one another in overlapping, parallelized condition.

According to the invention, loose masses of disordered fibers of spinnable length are subjected to the influence of an electric field of sufficient force and quality to polarize or orient the individual fibers comprising the masses, and straighten out all of the fibers in parallelized condition in a given direction determined by the lines of force in the field. More specifically, the invention contemplates establishing an electrostatic field, imparting relative movement to a surface with respect to the electric field, feeding the loose masses of fibers of spinnable length directly to the field, that is without the interposition of a screening device of any kind, whereby to orient the individual fibers in erect position against the said surface, subsequently laying the erect fibers back upon themselves in overlapping

5 parallelized condition, to form a seemingly continuous structure, and removing the structure from the surface. The structure comprising the overlapping fibers may be condensed or compacted to the desired size or conformed to the desired shape. The invention further contemplates the provision of electrode members, means for setting up an electrostatic field between the electrodes, a surface, means for imparting relative movement to the surface with respect to the field, means for feeding the loose masses of spinnable fibers directly to the field, means for laying the fibers in overlapping condition, and means for removing the overlapping fibers from the surface and means for condensing, compacting or shaping the structure.

2 In the accompanying drawings,

Figure 1 is a diagrammatic elevational view of apparatus which may be used in carrying out 10 the invention;

Figure 2 is a modification of the apparatus shown in Figure 1; and

Figure 3 is another modification of the apparatus of Figure 1.

25 Referring more specifically to Figure 1, the loose masses of disordered fibers are shown dropping from a hopper 2, onto an endless conveyor belt 5 which may be made of any non-conductive material, and which passes around pulleys 6 and 7. Conveyor belt 5 carries the fibers into an electric field of appreciable strength, for example, of 30 6,000 to 10,000 volts per inch, which is set up between two relatively flat electrodes 8 and 9. Under the influence of the so-called lines of force 35 of the electric field which, in the arrangement shown in Figure 1 are represented by lines 10, and which leave the electrodes perpendicularly to the surface, the fibers move away from the surface of belt 5 and are oriented in erect position on the under-surface of endless belt 11 which is of non-conductive material and which is positioned above belt 5. Belt 11 is positioned 40 so that it converges with respect to belt 5 in the direction of travel of the fibers on belt 5. As belt 11 travels around rollers 12 and 13, and pulley 13a, the oriented erect fibers shown at 45 14 brush against a fixed bar or rod 15 interposed between belts 5 and 11. Rod or bar 15 is preferably a grounded metallic member, so that any electrostatic charges carried by the fibers are discharged therefrom. The fibers are laid back upon 50 themselves with their ends overlapping to form a seemingly continuous structure in which all of the fibers are straightened out and arranged in parallelized overlapping condition. The struc-

ture 16 leaving the path defined by belts 5 and 11 passes over roller 16a and is directed to a condensing compacting, and/or conforming device. Where the fibers in the mat are not sufficiently coherent to enable the seemingly continuous structure to be conveyed to roller 16a without additional support, the structure may be conveyed to the condenser over a belt conveyor such as the endless belt conveyor shown at 19 in Figure 2. As shown, the structure is directed to a rotating cone-shaped condenser 17 driven by gear 17a where it is condensed to the desired size and given a false twist. Such a device is useful when the product it is desired to form is a spinnable sliver. The condenser 17 may be replaced by any other suitable condensing or compacting means, or by a conforming device to impart the desired shape to the structure. A driving mechanism (not shown) turns pulley 7 at a speed to move belt 5 through the electrostatic field at the desired speed. A similar device may be employed to drive pulley 13a, controlling the speed of movement of belt 11. The relative speeds of belts 5 and 11 may be varied but in general it is preferred to move belt 11 at a slower speed than belt 5, because such a speed differential permits a denser and more compact deposition of the erect fibers on belt 11. The density and compactness of the fibers on belt 11 may be controlled, also, by appropriate adjustment of the relative widths of belts 5 and 11.

In Figure 2 there is shown a modified arrangement, in which the fibers are fed from a hopper 2 into a blower 18. The masses of fibers, suspended in the current of air or other gas are opened and the separated individual fibers are dispersed directly into the electric field established between electrodes 8 and 9, and are oriented in erect parallelized position on the under surface of belt 11. In the arrangement shown in Figure 2, the belt 5 serves as a collecting surface for any fibers which do not enter the electric field directly from blower 18. If any such fibers are collected on belt 5, they are brought into the electrostatic field by travel of belt 5 around pulleys 6 and 7 and are oriented in erect position on belt 11. An endless belt 19, which passes around suitably driven pulleys 20 and 21, is positioned so that one end thereof projects into the exit end of the path defined between belts 5 and 11, and in close proximity to the under surface of belt 11. During the course of travel, of belt 11, the fibers oriented in erect position on the under surface thereof contact belt 19. The speed of belt 11 is greater than the speed of belt 19, so that when the erect fibers contact belt 19 they are laid back upon one another in overlapping parallelized condition. The overlapping parallelized fibers are removed from the surface of belt 11 in the form of a seemingly continuous structure or band 16 which is carried on the surface of belt 19 to the condensing device 17. Preferably, belt 19 is made of an electro-conductive material so that any residual electrostatic charges carried by the erect fibers emerging from the electrostatic field may be discharged, or a static eliminator may be associated with the belt for that purpose.

In Figure 3 there is shown a partial view of a modified form of apparatus which is similar to the apparatus illustrated in Figure 1, but which further includes a means, as illustrated a super-sonic vibrator 22, which may be positioned either below or above belt 5, for mechanically agitating the fibers prior to entry thereof into the electrostatic field. Such mechanical agitation serves to

assist in disintegrating the loose masses of fibers.

When the apparatus shown in Figure 2 is employed in carrying out the invention, the compactness and density of the erect fibers on the undersurface of belt 11 may be varied as desired by adjusting the speed of belt 11 with relation to the pressure under which the fibers are blown into the electric field.

Generally speaking, the spinnable fibers lend themselves more readily to electrostatic orientation when they are in substantially dry condition. In many cases, it may be desirable to pass the fibers through a heating zone prior to feeding them to the electric field. For this purpose there may be provided any suitable heating or drying means such as the heating chamber 3 shown in Figures 1 and 3. The chamber is provided with inner walls 4 comprising radiating surfaces which receive and reflect heat furnished by electric resistance units 4a. It is desirable to provide such a chamber, or equivalent drying means, when the fibers consist of or comprise regenerated cellulose. Such fibers have a normal atmospheric moisture content of from about 7 to 11% and it has been found that improved results are obtainable in the present case if the moisture content is reduced to about 1% or less prior to exposure of the fibers to the electrostatic field.

Electrode 8 is preferably connected to ground, as shown at 23, and electrode 9, insulated from ground, is maintained at high potential by connecting it to a high potential current source through conductor 24. The electrodes may be energized with a direct current, or with a rectified alternating current of high potential by means well known in the art. The electric field set up between the electrodes is uni-directional, electrode 9 being preferably negative with relation to electrode 8.

The electrodes 8 and 9 may be supported in any suitable manner, as by means of upright supports 25 and 26 respectively. The distance between the electrodes may be adjusted at will but, in general, the electrodes are positioned in comparatively close proximity to each other, depending upon the length of the spinnable fibers. In the apparatus as shown, belts 5 and 11 pass directly over the surfaces of electrodes 8 and 9, respectively, but such an arrangement is not required and the belts may pass over the electrodes in spaced relation thereto.

If desired, hopper 2 may be replaced by or be connected with a staple fiber cutting mechanism for cutting continuous filaments into fibers of spinnable length and, in such case, the invention makes possible a direct and most economical tow-to-top conversion. By such an arrangement a tow of freshly formed continuous filaments coming from a spinning machine, and which have been subjected to the usual after-treatments, may be cut to spinnable length and directly formed into a spinnable sliver, or a mat, web, bat or the like, without resort to an expensive combing operation, elimination of which greatly reduces the cost of the yarns and of the final products fabricated therefrom.

By the practice of the present invention it is possible to form a spinnable sliver, for example, directly from loose masses of disordered spinnable fibers of any material, whether artificial or natural, including fibers of regenerated cellulose, cellulose acetate, or other cellulose derivative, nylons or other polymeric materials, wool, cotton, etc., and where the masses comprise several mixed varieties of spinnable fibers, a better and more

uniform blending thereof is obtained. The sliver obtained by the method of the invention may be drafted and twisted in any well known or appropriate manner to form a yarn directly therefrom. Since the sliver is formed directly from the loose masses of disordered fibers without subjecting the fibers to picking, carding, combing or like mechanical operations, the fibers are not broken, and the surfaces thereof are not marred, so that in addition to the fact that the sliver is produced by a very economical method, yarns of superior quality are obtained.

It will be obvious that changes and modifications can be made in the above described apparatus and method within the scope of our invention which is not to be limited except as set forth in the appended claims.

We claim:

1. Apparatus for forming a seemingly continuous structure of indefinite length from loose masses of spinnable fibers which comprises electrode members, means for continuously maintaining an electrostatic field between the electrodes, means for continuously feeding the spinnable fibers to the field, an endless surface above the zone of the field to which the fibers are fed and having a discharge portion extending out of the field, means for continuously moving the surface through the field whereby the fibers are electrostatically erected against the surface in oriented and parallelized condition, another endless surface having a fiber receiving portion disposed closely beneath the fiber discharge end of the first-mentioned surface, and means for continuously moving the second surface in the direction of movement of the first surface whereby when the erected fibers contact the second surface all of the fibers are laid back upon themselves in overlapping parallelized condition on the second surface and carried thereby from the vicinity of the field in the form of a seemingly continuous structure.

2. Apparatus for forming a seemingly continuous structure of indefinite length from loose masses of spinnable fibers which comprises electrode members, means for continuously maintaining an electrostatic field between the electrodes, an endless surface, means for continuously moving the surface through the field, means for continuously feeding the spinnable fibers to the surface, a second endless surface above the zone of the field through which the first-mentioned surface carries the fibers and having a discharge portion extending out of the field, means for continuously moving the second surface through the field in the direction of movement of the first surface whereby the fibers carried on the first surface are electrostatically erected against the second surface in oriented and parallelized con-

dition, a third endless surface having a fiber-receiving portion disposed closely beneath the fiber discharge end of the surface against which the fibers are erected in the field, and means for continuously moving the third surface in the direction of movement of the first and second surfaces whereby when the erected fibers contact the third surface all of the erected fibers are laid back upon themselves in overlapping parallelized condition on said third surface and carried thereby from the vicinity of the field in the form of a seemingly continuous structure.

3. Apparatus for forming a seemingly continuous structure of indefinite length from loose masses of spinnable fibers which comprises electrode members, means for continuously maintaining an electrostatic field between the electrodes, an endless surface, means for continuously moving the surface through the field, means for continuously feeding spinnable fibers to the surface, a second endless surface above the zone of the field through which the first-mentioned surface carries the fibers and having a discharge portion extending out of the field, means for continuously moving the second surface in the direction of movement of the first surface, said second surface being arranged in a plane converging to the plane of the first surface in the direction of movement of the surfaces, a third endless surface having a fiber-receiving portion disposed closely beneath the fiber-discharge end of the surface on which the fibers are erected which extends out of the field, and means for continuously moving the third surface in the direction of movement of the first and second surfaces whereby when the erected fibers contact said third surface all of the fibers are laid back upon themselves in overlapping parallelized condition on the third surface and carried thereby from the vicinity of the field in the form of a seemingly continuous structure.
